No. 13,469

DEC 5, 1882

UNITED STATES PATENT OFFICE.

GEORGE H. HUGHES, OF NEW YORK, N. Y.

DESIGN FOR TABLE AND ENAMELED CLOTH.

SPECIFICATION forming part of Design No. 13,469, dated December 5, 1882.

Application filed November 4, 1882. Term of patent 3½ years.

To all whom it may concern:

Be it known that I, GEORGE H. HUGHES, a citizen of the United States, residing in the city, county, and State of New York, have invented certain new and useful Improvements in Designs for Table and Enameled Oil-Cloth, fully described and represented in the following specification and the accompanying drawings, forming a part of the same.

10 The principal feature of my design consists in parallel rows of figures having an ornamental border surrounding a female figure of Liberty embracing a standard of the United States colors with the left arm. Said figures are of concave shape at the sides and of convex shape at the top and bottom. Between the adjacent concave sides is the head of an Indian inclosed in an unequally-lobed quarterfoil, and between the said quarterfoils, in a line 15 with the rows of principal figures, is a scutcheon bearing the stars and stripes, and inclosed in a decorated oval border.

The ornamental borders about the female

figure, the Indian head, and the scutcheon may be slightly modified, as well as the subordinate ornaments between and in a line with the rows of principal figures, the essential parts being as described above and as represented in the fac-simile attached hereto, in which A A are the borders of the principal figures; B B, the figures of Liberty; C C, the quarterfoils; D D, the Indian heads; E E, the scutcheons, and F F the oval borders around them.

Having thus described my design, which 35 may be imprinted in any desired colors, I claim—

The design for table and enameled oil-cloth, substantially as shown and described.

In testimony whereof I have hereunto set 40 my hand in the presence of two subscribing witnesses.

GEO. H. HUGHES.

Witnesses:

THOS. S. CRANE,
J. B. NONES.
